STOREFRONT AWNING

Winston F. Bott, 1915 N. Lexington Blvd.,
Corpus Christi, Tex. 78409

Filed May 11, 1972, Ser. No. 252,523

Term of patent 14 years

Int. Cl. D25—02

U.S. Cl. D21—6 B

FIG. 1 is an isometric view showing the front, bottom and one end of the storefront awning which is adapted to be mounted on a store or building;

FIG. 2 is an end view of the storefront awning portion alone without any support therewith as viewed from one end of FIG. 1;

FIG. 3 is a plan view showing the upper portion of one portion of the storefront awning of FIG. 1, taken on line 3—3 of FIG. 2;

FIG. 4 is a view of a portion of the storefront awning of FIG. 1 looking at it from the lower end upwardly as indicated by line 4—4 of FIG. 2; and

FIG. 5 is a view of a portion of the storefront awning looking downwardly from the upper end thereof as indicated by line 5—5 of FIG. 2.

I claim:

The ornamental design for a storefront awning, substantially as shown and described.
